UNITED STATES PATENT OFFICE.

EDWARD H. JACOX, OF BASSETT, NEBRASKA.

RAILROAD TIE.

Application filed March 27, 1923. Serial No. 628,133.

To all whom it may concern:

Be it known that I, EDWARD H. JACOX, a citizen of the United States, residing at Bassett, in the county of Rock and State of Nebraska, have invented certain new and useful Improvements in Railroad Ties, of which the following is a specification.

This invention relates to railroad ties and has special reference to an all metal railroad tie.

One important object of the present invention is to improve the general construction of devices of this character.

A second important object of the invention is to provide an improved device of this character which is so arranged that the rails may be accurately gaged.

A third important object of the invention is the provision of an improved form of device of this character wherein the rails are securely clamped into gaged position.

With the above and other objects in view as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:—

Figure 1 is a section through a pair of rails showing the tie in use.

Figure 2 is a top plan view of the tie.

Figure 3 is a perspective view of a pair of the tie blocks.

In carrying out the invention in the present embodiment each tie consists of two pairs of tie blocks, the outer tie blocks being indicated at 10 and the inner tie blocks at 11. Each outer tie blocks 10 has a substantially rectangular body portion and upstanding from this body portion is a clamp member 12 shaped to conform to the side of a rail and extending up substantially level with the head, or top of the rail. Similarly, each of the blocks 11 has a spring, or clamp 13 but in the case of the blocks 11 the clamp 13 terminates with the head of the rail R 13 so as not to interfere with the flanges of the wheels running on the track. The blocks

10 and 11 have aligned openings 14 therein and are also provided with ears 15 so that they may be clamped securely to the respective rail R by means of clamp bolts 16. Through the openings 14 extend rods 17, one of which is provided on its inner end with a right hand thread 18 while the other is provided with a left hand thread 19 so that these two rods may have their inner ends connected by a turn buckle 20 of polygonal exterior. In assembling the device one of the clamps 10 and its mate 11 are placed in position on a rail and the bolts 16 inserted through the lugs 15 and tightened up so that this end of the tie is secured to the rail. Similarly, the remaining blocks 10 and 11 are aligned on the other rail with the first mentioned blocks and secured thereto. The rods 17 are now passed through the aligned openings 14 and the turn buckle 20 screwed thereon so that the rails are drawn together to the required amount for the condition of the track, that is to say, the rails on a straight piece of track using a standard gage are brought to such a point that the distance between the inner sides of the rail heads is 4 feet, 8½ inches, but this may be widened on curves depending on the degree of curvature in accordance with the usual engineering practice. Thus, by the use of this tie accommodation may be made for either straight or curved tracks without any alteration of the construction of the tie itself.

There has thus been provided a simple and efficient device of the kind described and for the purpose specified.

It is obvious that minor changes may be made in the form and construction of the invention without departing from the spirit thereof. It is not, therefore, desired to confine the invention to the exact form herein shown and described, but it is desired to include all such as properly come within the scope claimed.

Having thus described the invention what is claimed as new, is:—

A railroad tie consisting of a pair of outer blocks and a pair of inner blocks, rail engaging means on each block, opposed lugs on the sides of the inner and outer blocks

adapted to be disposed under the rails supported on the blocks, bolts passing through said lugs to hold the rail engaging means on the blocks into clamp relation with the 5 rails, rods extending through said blocks and terminating in spaced relation to each other at their inner ends, the inner ends of said rods being threaded right and left

handed respectively, and a turn buckle connecting said threaded ends.

In testimony whereof I affix my signature in presence of two witnesses.

EDWARD H. JACOX.
